DESIGN FOR A PAPER CUP DISPENSER

William J. Emerson, Kensington, Conn., assignor to Connecticut Paper Products Incorporated, Kensington, Conn., a corporation of Connecticut

Application November 4, 1939, Serial No. 88,049

Term of patent 14 years

To all whom it may concern:

Be it known that I, William J. Emerson, a citizen of the United States, residing at Kensington, in the county of Hartford and State of Connecticut, have invented a certain new, original, and ornamental Design for a Paper Cup Dispenser, of which the following is a specification, reference being had to the accompanying drawing forming a part thereof.

Fig. 1 is a view in perspective of a paper cup dispenser, showing my new design;

Fig. 2 is a rear view in elevation thereof; and,
Fig. 3 is a bottom view.

I claim:

The ornamental design for a paper cup dispenser, as shown.
